CLAIM

I claim the ornamental design for a writing pen, as shown and described.

DESCRIPTION

FIG. 1 is a perspective view of the writing pen showing my new design;

FIG. 2 is a front view thereof; and,

FIG. 3 is a left side view thereof; the right side view is understood to be a mirror image of the left side and is therefore not shown.

1 Claim, 2 Drawing Sheets

FIG. 1

FIG. 3
